UNITED STATES PATENT OFFICE.

JOSEPH GALLEAZZI, OF SAN FRANCISCO, CALIFORNIA.

ACCORDION.

1,050,270.

Specification of Letters Patent. Patented Jan. 14, 1913.

Application filed September 13, 1911. Serial No. 649,110.

To all whom it may concern:

Be it known that I, JOSEPH GALLEAZZI, a citizen of the United States, residing at San Francisco, in the county of San Francisco 5 and State of California, have invented new and useful Improvements in Accordions, of which the following is a specification.

This invention relates to the class of musical instruments, including accordions, 10 in which, by the pressure of a single piston or key, there are sounded several musical notes harmonizing with each other to produce a musical chord, as, for instance, the major or minor chord, the dominant seventh or the diminished seventh chords.

The object of the present invention is to provide an accordion having such an arrangement of keys or pistons as to greatly facilitate the operation of playing quickly 15 in succession a large number of such chords.

A further object is to provide an accordion in which the mechanism for playing such chords shall be simple, strong, durable, and not liable to get out of order.

25 In the accompanying drawing, Figure 1 is a plan view of the bass sounding board, showing also the key board, parts being removed, of an accordion constructed in accordance with my invention; Fig. 2 is a 30 similar view, the key board and upper portions of the apparatus being omitted; Fig. 3 is a similar view showing only the valves on said sounding board; Fig. 4 is a broken similar view showing rock shafts for producing chords, and showing in relation thereto a diagram of the chords so produced; Fig. 5 is a side view showing the relation of the keys; Fig. 6 is an enlarged view of a portion of Fig. 4; Fig. 7 is a dia- 35 grammatic view of the arrangement of keys and chords produced thereby; Fig. 8 is a transverse section of the sounding board and the key board on the line 8—8 of Fig. 2; Fig. 9 is a similar view the parts being 40 in a different position; Fig. 10 is a perspective view of a portion of the sounding board and a valve thereon; Fig. 11 is a similar view of a valve; Fig. 12 is a similar view of a lever.

50 Referring to the drawing, 1 indicates the outer case of an accordion, closed at one side by a sounding board 2, at which side is also attached the accordion bellows not here shown. In said sounding board are 55 formed valve openings 3, 4, controlled by valves 29, 30, in the manner hereinafter de-

scribed, said openings leading to reeds, which are here omitted as being of the usual construction and forming no part of my present invention. The opposite side of the 60 case is closed by the usual perforated cover, not here shown, provided with means by which it can be supported upon the arm of the operator. In the upper side 10 of said sound case are arranged rows of keys or pistons 11, movable in holes formed in said side 10 and connected at their inner ends to rods 12, the inner ends of which are flattened and pivotally connected to the ends of arms 13 of bell crank levers 9, which arms move in 65 slots 14 cut in frame pieces 15 extending longitudinally within the case and their ends being secured on standards 16, which in turn are secured upon the outer side of the sounding board. Stop pieces 17 are secured by 70 brackets 18 to the frame pieces, against which stop pieces the edges of said arms are adapted to abut. Said stop pieces thus limit the outward movement of said arms and of the keys or pistons. The lower arms of 75 said bell crank levers 9 are bent at right angles downwardly, and carry at their extremities transverse pins 19, 20, which pass beneath rocking arms 21, 22, extending from longitudinal rock shafts 23, 24, the ends of 80 said rock shafts being pivotally supported in said standards 16. These shafts are arranged in two series of twelve each. The shafts 23, nearer the pistons or keys 11, are adapted to be rocked by the keys or pistons 85 11 of the two rows most distant from the hand of the operator, and the shafts 24 by those of the four nearer rows. From said rock shafts 23, 24, extend arms 25, 26, which pass respectively through apertures 27, in 90 lugs 28, cut out from and extending upwardly from the valves 29, 30 pivotally attached to the sounding board by two screws 31, loosely passing through holes 32 in said valves, said valves thus being each enabled 95 to rock upon said screws as on a pivotal axis. The under sides of said valves are covered with felt or other suitable material, which also closes the apertures made by forming the lugs 28. Said valves close the 100 openings 3, 4, in the sounding board, but when the pistons 11 are depressed, the corresponding valves are raised in the manner already explained and air is enabled to pass through said valve openings, thus causing 105 vibration of the corresponding reeds, and producing musical tones. When the pres- 110

sure is removed from the pistons, the valves are closed by springs 34, 35, of which each spring 34 presses upwardly an arm 36 extending from the corresponding valve 29 5 beyond its pivotal axis, and each spring 35 presses directly down on the corresponding valve 30.

There are 18 keys in each of the two rows of keys or pistons 11 which actuate the 10 shafts 23, or 36 keys in all. This permits the key corresponding to each musical note, of which there are twelve in an octave, to be repeated three times. That is, for actuating the same rock shaft 23, there are provided 15 three separate keys, and these keys are located at positions on the key board remote from each other. Thus the player is able, in all positions of his hand, to press one or the other of these three keys easily and rapidly to operate the corresponding rock shaft 23 to produce the tone desired. On depressing any one of the keys of the other four rows, not only is the shaft 24 rocked which causes a vibration producing any single 25 musical note, but also other shafts are simultaneously rocked and other musical notes are produced. Thus, upon depressing any one of the keys in the lowermost row of the four, or the third from the bottom 30 of all the rows, shafts 24 are rocked which open valves 30 to cause notes to be produced which form the major chord of a musical note. On depressing a key in the fourth row from the bottom, musical tones are produced which form the minor chord of a 35 note. On depressing one of the keys in the second row from the top the dominant seventh chord of a note is produced. On depressing a key in the uppermost row, the diminished seventh chord of a note is produced. This result is effected by the following mechanism. The transversely extending pins 20, before mentioned, are each sufficiently long to extend, not only under 40 the arm 22 corresponding to the shaft 24 which opens the corresponding valve 30, but also under the arms 22 connected to other shafts 24. Thus, if a key be depressed which is in the lowermost of the four rows, 45 as, for instance, that corresponding to the note C, not only is the valve opened which controls the production of the note C but also the valves which control the production of the notes E and G, so as to produce the 50 major chord of the key of C.

Referring more particularly to Figs. 4 and 5, and to Fig. 6 which is an enlarged plan view of that part of Fig. 4 which illustrates mechanism corresponding to the musical note C, if the key corresponding to this note be depressed in the major scale row, that is, the fourth row from the outside, the bell crank lever 9 is actuated which lies on the extreme left, and from which extends a 55 pin 20 entirely to the right, which pin then

passes in order under the arms 22 attached to the shafts 24 which open the valves which produce the tones of the notes E, G and C, and no others, so that the major chord of the key of C is produced. If now the key corresponding to the same note be depressed in the minor chord row, that is, the third row from the outside, the next bell crank lever to the right is then actuated, and it will be seen that a pin 20 extends from this bell crank lever entirely to the right, and under, in order to the right, the arms attached to the rock shafts corresponding to the notes C, G and D sharp, so that the minor chord of the key of C is produced. If the corresponding key in the second row from the outside, or the row of the dominant seventh, be depressed, then the third bell crank lever in order to the right is actuated, from which bell crank lever 75 there extends a transverse pin 20 both to the left and to the right, passing in order, commencing on the left, beneath the arms attached to the rock shafts which produce the notes A sharp, E, G, and C, giving the chord 80 of the dominant seventh. Finally if the corresponding key of the outside row, the row of the diminished seventh, be depressed, then the bell crank lever on the right is actuated, and a pin 20 extends therefrom passing 85 in order, from left to right, beneath the arms attached to the rock shafts which open the valves which control the production of the notes C, D sharp and A, giving the chord 90 of the diminished seventh. This arrangement is also indicated by the diagram 95 shown in the upper part of Fig. 4, in which the notes, the production of which is controlled by the depression of a corresponding key in the four rows, are indicated by the names of said notes within circles 100 which are connected together by lines 39. 105

The arm 36 of each valve 29 extends over one end of a lever 41 secured to a sleeve 42 on a longitudinal shaft 43, the other end of which lever 41 passes beneath an extension 40 on the corresponding valve 30, the result of which is that, if any key in the two innermost rows is depressed, not only is the corresponding valve 29 opened, but also the valve 30, thus causing notes from the corresponding reeds to be sounded and reinforcing the original tones. 110

I claim:—

1. In an accordion or the like, the combination of a sounding board having openings, valves for closing said openings, a plurality of parallel rock shafts, one for each valve, an operative connection between each rock shaft and its corresponding valve whereby 120 the rocking of the shaft opens said valve, arms extending from each rock shaft, levers 125 operatively connected to the respective arms, and keys operatively connected to the respective levers. 130

2. In an accordion or the like, the combination of a sounding board having openings therein, valves for closing said openings, rock shafts for the respective valves, operative connections between said rock shafts and valves, whereby the rocking of each shaft actuates the corresponding valve, arms extending from each rock shaft, bell crank levers corresponding to said arms, operative connections between said bell crank levers and the respective arms, whereby each arm can move independently of the bell crank lever, but the movement of the bell crank lever correspondingly moves the arm, 10 keys, and operative connections from the keys to the bell crank levers.
3. In an accordion or the like, the combination of a sounding board, two rows of openings therein, two rows of valves arranged to close the respective openings, a longitudinal shaft between the two rows of valves, levers pivoted on said shaft corresponding to the respective valves of the two rows, each valve of one row being oper- 15 atively connected with the corresponding lever to move the same when the valve is opened and said lever being operatively connected with the corresponding valve of the other row, to open the same when so moved.
4. In an accordion or the like, the combination of a sounding board having openings, valves for closing said openings, rock shafts corresponding to the respective valves, operative connections between said rock shafts and their respective valves, keys, levers 20 operatively connected to said keys, arms extending from the respective rock shafts, and a pin extending laterally from each lever and adapted to engage a plurality of such arms to simultaneously rock a plurality of such shafts.

In testimony whereof I have hereunto set my hand in the presence of two subscribing witnesses.

JOSEPH GALLEAZZI.
